UNITED STATES PATENT OFFICE.

MARTIN MAXIAN, OF JOHNSTOWN, PENNSYLVANIA.

FLYCATCHER.

Application filed August 2, 1921. Serial No. 489,238.

To all whom it may concern:

Be it known that MARTIN MAXIAN, a citizen of the United States of America, residing at Johnstown, in the county of Cambria and State of Pennsylvania, has invented new and useful Improvements in Flycatchers, of which the following is a specification.

The object of the invention is to provide a simple and efficient fly catcher adapted for 10 location in an upright or standing position suitable for support by a table or like article of furniture under conditions minimizing the risk of coming in contact with surrounding objects and therefore relieved of 15 the objections to which fly paper and similar forms of fly and insect traps are exposed,—namely that there is a liability of inadvertently placing other objects upon the same or of having the paper disturbed or 20 placed by gusts of wind and coming in contact with other objects; and with these objects in view the invention consists in a construction and combination of parts of which a preferred embodiment is shown in the accompanying drawings, wherein:—

Figure 1 is a view of a fly catcher or trap embodying the invention.

Figure 2 is a sectional view of the same.

The device consists essentially of a holder

30 10 having legs or uprights 11 to space the same from a supporting surface such as a table top or the like, and a replaceable or interchangeable unit 12 adapted to be supported by the base and consisting of a conical standard 13 provided with a base 14 adapted for engagement with the holder which is provided with clips 15 for engaging the side edges thereof, said holder having a grip or handle 16 by which it may be readily carried from place to place with the trap unit supported thereon, and the base being provided with a finger hold 18 to facilitate the disengagement thereof from the holder.

The surface of the standard is provided

with an adhesive coating of a character 45 adapted to attract and trap the flies or other insects and to prevent the material constituting the adhesive substance from coming in contact with surrounding objects when, as in particularly hot weather the same becomes 50 liquid and flows downward upon the standard a drip trough or cup 17 is arranged around the bottom of the standard or shaft on the base.

The foundation of the unit, inclusive of 55 the shaft or standard, the drip trough or cup and the base is preferably cardboard or heavy paper which by reason of its shape is adapted to maintain the upright position indicated, and at the same time may be 60 manufactured at a small cost and as a means of facilitating the commercial handling of the device the foundation may be packed and shipped without the adhesive coating and the latter may then be applied when it is desired to use the unit or after it has been 65 set up upon the holder, so that the trough at the bottom is in a position to catch any overflow and prevent the same from reaching adjacent articles of furniture or other objects.

Having described the invention, what is claimed as new and useful is:—

A fly catcher comprising a holder provided with legs to space the same from a supporting surface and formed on its upper surface with oppositely disposed clips, said holder having a handle, and a replaceable unit having an adhesively coated surface and provided with a base for engagement 75 with the clips on the holder, the said replaceable unit being formed with a drip cup adjacent the base and with a finger hold for withdrawing and inserting the base in engagement with the clips.

In testimony whereof he affixes his signature.

MARTIN MAXIAN.
